UNITED STATES PATENT OFFICE.

ALFRED ARNT, OF BAINBRIDGE TOWNSHIP, BERRIEN COUNTY, MICHIGAN, ASSIGNOR OF ONE-HALF TO EDWARD HENDRICKS, OF BENTON HARBOR, MICHIGAN.

COMBINED FOLDABLE CAMP-STOOL AND COT.

1,188,234.

Specification of Letters Patent. Patented June 20, 1916.

Application filed July 7, 1915. Serial No. 38,514.

To all whom it may concern:

Be it known that I, ALFRED ARNT, a citizen of the United States, residing at Bainbridge township, in the county of Berrien 5 and State of Michigan, have invented new and useful Improvements in Combined Foldable Camp-Stools and Cots, of which the following is a specification.

The present invention relates to improvements in the construction of furniture.

In carrying out my invention it is my purpose to provide an article of furniture which may be readily converted from a chair or stool to a couch or cot, or vice versa and 15 which, when not in use, may be folded to provide a small bundle or package for transportation or storage.

It is a further object of my invention to provide an article of this character which 20 shall embody the desirable features of strength, durability, simplicity, and cheapness in construction.

With the above and other objects in view, the improvement resides in the construction, 25 combination and arrangement of parts set forth in the following specification and falling within the scope of the appended claims.

In the accompanying drawings there has been illustrated a simple and preferred embodiment of my improvement reduced to practice, it being understood that the nature 30 of the invention is such that the same is subject to various changes in the details of construction without departing from the scope 35 of the appended claims.

In the drawings: Figure 1 is a plan view of an article of furniture constructed in accordance with the present invention showing the same in the form of a couch, Fig. 2 40 is a central vertical longitudinal sectional view through the same; Fig. 3 is a detail elevation illustrating the manner in which the brace member is arranged upon the sides at the hinge connection of the said sides,

Fig. 4 is a detail sectional view taken through one of the hinged sides and illustrating the manner in which the legs are sustained in an adjusted position with relation to the said side, Fig. 5 is a detail longitudinal sectional view through the sides at the hinged connection thereof, Fig. 6 is a central vertical longitudinal sectional view through the device in the form of a chair or camp stool, Fig. 7 is a side elevation illustrating the device in its folded or collapsed

condition, and Fig. 8 is a detail view, partly in elevation and partly in section to illustrate the manner in which the canvas body is sustained to provide the back of the chair.

In the reduction of my improvement to practice I provide longitudinal or side members 1—1, each comprising a pair of alining substantially rectangular bars which are approximately centrally hingedly secured, as at 2. The members 1, adjacent their ends, 60 are each provided with elongated slots 3 and 4 respectively, the slots 4 being of a materially greater length than the slots 3. These slots are adapted to receive transverse connecting members or rods 5 and 6 respectively, and the said members 5 and 6 are connected with the leg members 7 and 8 respectively. The leg members 7 are secured to the rod 5 at the ends thereof and are provided with a transverse brace or connecting 65 member 9, which, when the device is set up as a couch, is adapted to underlie the sides which are provided with the slots 3. These members or the sides 1 are provided with a plurality of apertures 10 which are arranged 70 at a right angle with respect to the elongated slots, and the numerals 11 designate pins or stops which are adapted to pass through certain of the apertures 10 and contact with the rod 5 to sustain the said rod in a longitudinally adjusted position within the slots 3. The elements in the sides which are provided with elongated slots 4 at a suitable 75 distance from the said slots are provided with an additional transverse connecting 80 rod 12 and secured to this rod and to the rod 5 is a canvas body 13. It will be noted that by providing the spaced openings 10, the rod 5 may be moved longitudinally within the slots 3 and sustained in proper position 85 within the slots to draw the canvas body 13 taut and the said rods may be sustained in such position by the insertion of 90 the pins 11.

In order to sustain the side members 1 in 100 proper alinement when the device is set up as a couch, one of the said members is provided at its meeting end with a dowel 14 which is adapted to be received in the socket 15 in the co-acting member and further to 105 add to the rigidity of the device I provide catch members in the nature of plates 16 which are adapted to co-engage with both of the members comprising each of the sides. As stated, the catch member 16 comprises a 110

plate that is hingedly secured, as at 17, to one of the elements of the side. The said side, at a suitable distance from its pivot, is formed with an inturned lug 18, and the co-
5 extending element of said side is provided with additional lugs 19 and 20, one of the same being arranged in a line with the lug 18 and the other being disposed below the plane of the lugs 19 and 20. The plate 16
10 is provided upon what I will term its upper edge with spaced depressions 21 and 22 and upon its bound edge and adjacent its end with a similar depression 23. Before the elements comprising the sides 1 are swung
15 to their horizontal position, each of the plates 16 is moved to bring its depression 23 in position to receive the stud 20 in the depression. A downward movement of the elements comprising the sides will cause the
20 studs 18 and 19 to be received within the depressions 21 and 22 in said plate 16. All of these studs may be headed if desired, and by such an arrangement it will be noted that the device is rendered strong and effective
25 at the joint thereof.

The rod 6 passes through the leg members 8 at approximately the central portion thereof, the said legs 8 being approximately twice the length of the leg members 7, and
30 connecting the said legs 8 at one of the ends thereof is a bar or round 24. Arranged upon this round is a canvas 25, and the opposite end of said canvas is secured to a bar or round 26 that is secured to the sides 1 forward of the slots 4 and opposite but spaced from the bar 12. This canvas provides the head for the couch, as well as the seat for the stool when the device is set up as such. The legs 8 are provided on one of their
35 edges with studs or pins 27 which are adapted to be passed through suitable openings in the opposite ends of a removable brace bar 28, the said brace bar underlying the elements comprising the sides 1 and so forming
40 a means for retaining the legs 8 at a desired inclination with relation to the said sides. The members provided with the slots 4 are formed with a plurality of apertures 29 which communicate with the said sockets, and these apertures are adapted to receive
45 suitable pins 30 forming stop members which contact with the rods 6 to prevent the sliding of the said rod within the slots 4.

The side members 1 to which the brace plates 16 are pivotally connected are provided with additional studs 31 which receive the depression 23 in the said plates 16 when the device is set up to provide a camp stool or chair and also one of the elements comprising each of the sides 1 is provided with a hook 32 which is adapted to engage in an eye 33 in the co-acting side element when the sides are folded against each other and the device converted into a chair. When in
60 such position, the legs 7 are swung against

the elements comprising the sides 1 to which they are pivotally connected by the rod or bar 5, and as the brace 9 contacts with the second element of the sides the same will be effectively sustained in this position. The pins 30 have been previously removed to permit of the rod 6 sliding in the slots 4 so that the ends of the side members 1 provided with the said slots 4 in reality form one of the legs of the chair. 75

The canvas body 13 has passed between the fold thereof a brace bar 33^a, the said bar being preferably round in cross section for the major portion of its length and having its ends flat and provided with perforations 80 to receive the dowels 14, and by this arrangement it will be noted that the canvas 13 provides the back of the chair. The canvas back may be adjusted by moving the bar 5 through the slots 3 so that the same may 85 be retained in a proper taut condition and when in such condition the pins 11, which it should have been stated, have been previously removed from the apertures 10, will again be inserted within certain of said 90 apertures to engage with the rod 5 to hold the canvas 13 taut, as stated.

When the device is collapsed or folded the leg members 8 are swung upon their pivotal connection with the bar or rod 6 against the 95 elements comprising the sides 1 provided with the elongated slots 4.

From the above description, taken in connection with the accompanying drawings, the simplicity of the device, as well as the 100 advantages thereof will, it is thought, be perfectly apparent to those skilled in the art to which such invention appertains without further detailed description.

Having thus described the invention, what 105 I claim is:

1. In a convertible and collapsible article of furniture, hingedly connected side bars, brace members at the hinged connection of the said bars, the members comprising each 110 of the bars having elongated slots, rods passing through the slots, leg members secured to the rods, brace members for the legs underlying and contacting with the side bars, one pair of said leg members being centrally connected with one of said rods, a round connecting the ends of these leg members, spaced rounds connecting the side bars, a canvas body upon one of these rounds and the mentioned round of the mentioned legs, 120 and a second canvas body secured to the other round and to the connecting bar for the other pair of legs.

2. In a collapsible article of furniture adapted to be converted from a camp stool 125 to a chair or vice versa, side bars, comprising each two alining members which are hingedly connected, studs upon the bars adjacent the hinged connection thereof, a brace member pivoted to one of the bars and hav- 130

ing depressions entering from its opposite sides adapted to engage with the studs when the device is set up as a couch, longitudinally movable leg members arranged adjacent the 5 ends of the bars, means for sustaining the leg members adjusted upon the bars, brace rods for the leg members contacting with the bars, one pair of leg members being of a greater length than the other and having 10 their ends connected by a round, a canvas body secured to the round and secured to the bars to which the said leg members are connected, a second canvas body also secured to said bars, and the last mentioned canvas 15 being connected with the other leg members.

3. In a foldable article of furniture adapted to be converted from a canvas stool to a couch or vice versa, side bars comprising each a pair of hinged members having 20 abutting ends, dowels upon the ends of one of said members, the other members being provided with sockets to receive the dowels, said bars being provided with elongated slots adjacent their ends, rods passing 25 through the slots, legs secured to the rods, brace members for the legs engaging with the bars, means for sustaining the rods in a longitudinally adjusted position in the slots, one pair of said legs being of a greater 30 length than the other pair, a round connecting the ends of the last mentioned legs, a canvas body secured to the round, a second round connected with the bars receiving the canvas body, a rod passing through the bars 35 adjacent the said canvas body, a second canvas body secured to this rod and with the rod connecting the other pair of leg members.

4. In a foldable article of furniture adapted to be converted from a camp stool to a couch or vice versa, side bars having slots 40

adjacent their ends, said bars comprising each a pair of hinged members, a dowel upon the end of one of said members, the second members having their ends provided 45 with sockets adapted to receive the dowels when the side members are in alinement and the device set up as a couch, rods passing through the elongated slots, legs secured to the rods, brace members for the legs engaging the bars, means, comprising removable elements passing through the slots and contacting with the bars for sustaining the bars adjusted in the slots, one pair of said 50 leg members being of a greater length than 55 the other, a round connecting these leg members, a canvas body upon the round, said body being secured to the bars to provide a head when the device is set up as a couch and a seat when the device is set up as a 60 stool, a second canvas body also secured to the bars adjacent the seat, this last mentioned body being also connected with the rod providing the connecting member for the other pair of legs, means for connecting 65 the elements comprising the sides when the same are swung against each other when the device is set up as a stool, and a rod having flattened ends provided with openings adapted to be arranged between the 70 fold of the last mentioned canvas body and to be received in the mentioned dowels of two of the members comprising the sides when the device is set up as a stool and whereby the said last mentioned canvas body 75 provides the back for the stool.

In testimony whereof I affix my signature in presence of two witnesses.

ALFRED ARNT.
